UNITED STATES PATENT OFFICE.

FRANCIS E. DROLL, OF ST. CHARLES, MISSOURI.

BREECHING-BUCKLE.

SPECIFICATION forming part of Letters Patent No. 249,597, dated November 15, 1881.

Application filed August 12, 1881. (No model.)

To all whom it may concern:

Be it known that I, FRANCIS E. DROLL, a citizen of the United States, residing at St. Charles, in the county of St. Charles and State 5 of Missouri, have invented certain new and useful Improvements in Breeching-Buckles; and I do hereby declare the following to be a full, clear, and exact description of the invention, such as will enable others skilled in the art to 10 which it appertains to make and use the same, reference being had to the accompanying drawings, and to the letters or figures of reference marked thereon, which form a part of this specification.

15 My invention relates to that class of devices which are used to connect the back and hip straps of harness, and provision is also made for supporting the traces when the animal is unhitched; and it consists of two plates having 20 certain details of construction, which will be hereinafter fully described, and specifically pointed out in the claims. These objects I attain by the mechanism illustrated in the accompanying drawings, in which—

25 Figure 1 is a perspective view of the bottom plate. Fig. 2 is a like view of the top plate, and Fig. 3 shows the two plates united together and back and hip straps and chafe-leather secured thereto.

30 Similar letters refer to like parts in the several views.

A represents the bottom plate, which consists of two side bars, a a , a solid end bar, a' , at the rear end, and a pointed extension, a'' , 35 at the front end. The two end bars or extensions are provided with holes or perforations for uniting the plate to the chafe-leather. The frame is provided with a central transverse bar, a^3 , and two short longitudinal bars, a^4 a^4 , in the 40 center of the frame, which intersect and are connected with the central transverse bar. The central longitudinal bars carry short studs or pins a^5 a^5 , which are adapted to engage with holes in the back and hip straps. The side bars are constructed with short lugs or projections near their center, which project upwardly, and which, when the top plate is applied, 45 form side slots or openings for the passage of the back and hip straps.

50 The top plate, B, is of the general form and outline of the bottom plate, excepting that both

end bars are of substantially the same form, or, in other words, the front extension is omitted from this plate. The plate B has side bars, b b , and solid end bars, b' b' , which have holes or perforations coincident with the holes in the bottom plate, for a purpose hereinafter to be explained. The end bars are each provided with a tooth which projects inwardly toward the center of the frame to prevent any undue 60 play of the straps. The plate B is provided with an arch or bridge, B' , which extends from one of the side bars to the other, and consists of two curves or loops, which are adapted to receive and support the traces when the animal 65 is unhitched.

The operation of the device is as follows, viz: The bottom plate is laid upon the pad-leather, the back and hip straps are adjusted on the studs, the top plate is laid on with the holes or 70 perforations registering with those in the bottom plate, and the two plates and pad-leather are all secured together by means of rivets, which are passed through the holes in the plates and afterward upset. When the two 75 plates are united they form a sort of box, having short studs or pins for securing the back and hip straps and forming slots at both sides for the passage of these straps, as will be readily apparent. By means of my invention I am 80 enabled to save leather and avoid sewing, as in the ordinary method of connecting these parts of harness.

While I prefer to use both plates, as above described, it is evident that in some instances 85 they may be used separately with advantage. In cart-harness, for example, the top plate may be dispensed with, the lower plate may be united to the chafe-leather, and the hip and back straps secured over the studs, the two upwardly-projecting lugs on the side bars in this instance 90 serving the purpose of keeping the straps apart.

By my construction I am enabled to furnish harness-makers a breeching-buckle that is readily adapted for three distinct kinds of harness, and one which effects a saving both of material and labor in the construction of a harness. 95

Having thus fully described my invention, what I claim is—

1. The plate A, having side bars with central upwardly-projecting lugs, a perforated rear end bar, a perforated front extension, a 100

central transverse bar, and two central longitudinal bars carrying studs or pins, substantially as set forth.

2. The plate A, having side bars with upwardly-projecting lugs, a perforated rear end bar, a perforated front extension, a central transverse bar, and two central longitudinal bars, in combination with the plate B, having corresponding side and end bars and a central transverse bridge or arch, forming two loops,

and adapted to be applied to a harness substantially in the manner and for the purpose set forth.

In testimony whereof I affix my signature in presence of two witnesses.

FRANCIS E. DROLL.
